(57) **CLAIM**

The ornamental design for an combined emergency rechargeable flashlight and soft glow night light, as shown and described.

DESCRIPTION

FIG. 1 is a front view showing my new design.

FIG. 2 is a rear view thereof.

FIG. 3 is a left end view thereof.

FIG. 4 is a right end view thereof.

FIG. 5 is a top view thereof.

FIG. 6 is a bottom view thereof.

FIG. 7 is a perspective view thereof.

FIG. 8 is another perspective view thereof; and,

FIG. 9 is another perspective view thereof.

The surface(s) or portion(s) of the article not shown in the drawing or described in the specification form(s) no part of the claimed design.
